US00D595422S

(12) **United States Design Patent**
Mustapha

(10) **Patent No.:** **US D595,422 S**
(45) **Date of Patent:** **** Jun. 30, 2009**

(54) **SUPPORT DEVICE FOR INTERVENTIONAL INSTRUMENTS**

(75) Inventor: **Jihad Mustapha**, Ada, MI (US)

(73) Assignee: **Wire • Caddy, LLC**, Ada, MI (US)

(**) Term: **14 Years**

(21) Appl. No.: **29/320,016**

(22) Filed: **Jun. 18, 2008**

(51) **LOC (9) Cl.** **24-02**

(52) **U.S. Cl.** **D24/227**

(58) **Field of Classification Search** **D24/108, D24/127-130, 216, 224, 227-232; 422/63-64, 422/99-104, 250, 266, 297, 300, 476; 211/74, 211/71.01; D3/304-315**

(57) **CLAIM**

The ornamental design for a support device for interventional instruments, as described and shown.

DESCRIPTION

FIG. 1 shows a perspective view of a support device for interventional instruments that incorporates my design.

FIG. 2 shows a front view of the support device for interventional instruments shown in FIG. 1.

FIG. 3 shows a back view of the support device for interventional instruments shown in FIG. 1.

FIG. 4 shows a top view of the support device for interventional instruments shown in FIG. 1.

FIG. 5 shows a right side view of the support device for interventional instruments shown in FIG. 1.

FIG. 6 shows a left side view of the support device for interventional instruments shown in FIG. 1; and,

FIG. 7 shows a bottom view of the support device for interventional instruments shown in FIG. 1.

Any broken lines in the drawings depict environmental structure that forms no part of the claimed invention.
